US0D1056521S

(12) **United States Design Patent** (10) Patent No.: **US D1,056,521 S**
(45) Date of Patent: ** Jan. 7, 2025

(54) **SOFA**

(71) Applicant: **EDRA SPA**, Perignano (IT)
(72) Inventor: **Francesco Binfarè**, Perignano di Lari (IT)
(**) Term: **15 Years**
(21) Appl. No.: **35/516,497**
(22) Filed: **Dec. 3, 2022**

(80) **Hague Agreement Data**

Int. Filing Date: **Dec. 3, 2022**
Int. Reg. No.: **DM/226963**
Int. Reg. Date: **Dec. 3, 2022**
Int. Reg. Pub. Date: **Mar. 3, 2023**

(30) **Foreign Application Priority Data**

Jun. 3, 2022 (EM) 009050693
(51) LOC (15) Cl. **06-01**
(52) U.S. Cl.
USPC **D6/334; D6/367; D6/381**
(58) **Field of Classification Search**
USPC D6/334, 335, 336, 364, 371, 374, 377, D6/378, 381
CPC A47C 17/04; A47C 7/541
See application file for complete search history.
